UNITED STATES PATENT OFFICE.

ASHTABULA GAINES, OF WESTMINSTER, SOUTH CAROLINA.

HAMMER ATTACHMENT FOR ANVILS.

1,150,262.

Specification of Letters Patent. Patented Aug. 17, 1915.

Application filed January 25, 1915. Serial No. 4,278.

To all whom it may concern:

Be it known that I, ASHTABULA GAINES, a citizen of the United States, residing at Westminster, in the county of Oconee and State of South Carolina, have invented certain new and useful Improvements in Hammer Attachments for Anvils, of which the following is a specification, reference being had to the accompanying drawings.

10 My invention relates to iron working, and particularly to means for operating a sledge hammer in conjunction with an anvil.

The primary object of my invention is the provision of a foot controlled hammer operating means so constructed that the point of contact of the hammer with the anvil may be shifted or adjusted without materially shifting longitudinally the fulcrum point of the actuating lever or treadle.

20 A further object is to so support the hammer shank that it may be shifted vertically and at the same time horizontally toward the anvil to thereby alter not only the point of contact of the hammer with the anvil, 25 but also shift the angle of inclination of the shank, and in this connection to provide means whereby the angle of the hammer face may be changed with relation to the face of the anvil, either independently of 30 the shifting of the hammer shank, as before stated, or coördinately therewith.

Still another object is to improve upon constructions of this character by simplifying the mechanism, rendering it more positive in its action and making it more fully 35 under the control of the blacksmith, so that blows may be delivered with a greater or less force and so that the head of the sledge hammer may be applied to suit the character 40 of the work being done.

Other objects will appear in the course of the following description.

My invention is illustrated in the accompanying drawings, wherein—

45 Figure 1 is a perspective view of an anvil with my attachment applied thereto; Fig. 2 is a fragmentary elevation, partly in section, of the sledge hammer supporting means, showing the manner in which it may be adjusted; Fig. 3 is a fragmentary transverse section to show the means for adjusting the sledge hammer.

50 Referring to the drawings, 2 designates an anvil of the usual form and 3 the anvil block

upon which the anvil is mounted. As illustrated, in order to dispose the parts at all times in proper relation, the anvil block is supported upon a base 4 and rigidly connected thereto in any suitable manner. The end of the base 4 opposite the end of the block is illustrated as formed with the upstanding supporting member 5.

Mounted upon the member 5 and extending up therefrom are the spaced standards 6, the upper portions of which are longitudinally slotted as at 7. These standards are rigid and are held securely to the supporting member 5. Disposed between these standards is a brace 8 which is securely connected with the standards in a manner which will be later stated, and which at its other end is disposed between ears 9 projecting from the anvil block. The brace 8 is pivotally connected to the ears 9 by means of a transverse bolt 10. Rigidly connected 75 to the outer end of the brace 8 and extending up therefrom at right angles thereto are the hammer supporting members 11, preferably formed of angle iron. These members 11 are disposed against the outer faces 80 of the standards 6, and passing through the members 11, through the slots 7 in the standards 6, and through the outer end of the brace 8, is a bolt 12. One end of this bolt is provided with any suitable head and the 85 other end is provided with a clamping nut 13 having a handle whereby it may be readily turned. The brace 8 at its outer end is formed with a short longitudinal slot 14 through which the bolt 12 passes. 90 The brace 8 is connected with the upper ends of the hammer supporting members 11 by means of diagonal braces 15 which are also 95 preferably formed of angle iron.

Extending downward from the brace 8 and attached thereto in any suitable manner is a bracket 16 braced by means of a diagonal brace 17, to the lower end of which bracket and brace is pivotally connected a lever 18. This lever extends nearly to the anvil block, and at its end adjacent the anvil block is provided with the oppositely disposed plates 19 forming extensions on the lever between which is pivoted a link 20 which passes upward and rearward through a slot 21 formed in the brace 8. Attached to the lever 18, and specifically on each side of the plates 19, is a split ring or yoke 22,

the ends of which are flanged as at 23 to bear against the plates 19, a bolt or like fastening device extending through the ends of the yoke, and through these plates and the lever 18. The plates 19 at their forward ends are laterally bent as at 24, these laterally bent ends being riveted as at 25 to the yoke so as to brace the yoke rigidly and hold it in rigid alinement with the lever 18. 5 These braces 24 of course do not touch the anvil block 3, but are spaced therefrom sufficiently to permit the free movement of the lever 18.

Disposed upon the ring 22 directly in line 15 with the lever 18, is a treadle 26 which is attached to the yoke or ring 22 in any suitable manner.

Pivoted between the upper ends of the hammer supporting member 11 is the sledge 20 hammer shank 27. This shank is pivoted upon a pivot pin or bolt 28 passing through the upper ends of the members 11, and this shank 27 extends rearward beyond this pivot pin as at 29. A clevis 30 is pivotally attached to this rearwardly projecting end 29, and to this clevis is connected the helical spring 31, which at its lower end is connected to a bolt 31^a extending through the brace 8 at an angle thereto. This spring 31 is a 30 contractile spring and acts to yieldingly hold the hammer shank in the position illustrated in dotted lines in Fig. 1, but will yield to permit the hammer shank to rotate in the direction of the arrow, Fig. 1, so as 35 to cause a blow to be struck upon the anvil.

The link 20 at its upper end is pivotally connected to a collar 32, which collar is adjustable along the hammer shank, but is held clamped in any adjusted position thereon by 40 means of the bolt 33 which passes through extensions of the collar and through the link 20. When this collar 32 is clamped upon the hammer shank, the link 20 has pivotal engagement with the plates 19 so that a 45 pressure on the yoke by means of the treadle 26 will cause the hammer shank to be pulled down. When the pressure on the treadle 26 is released the spring 31 will act to draw the hammer shank upward in a manner obvious from the illustration.

Preferably the hammer shank 27 is made of wood reinforced by longitudinally extending side plates 34 on the rear side faces of the hammer shank, these side plates being 55 riveted or bolted to the shank.

The hammer head 35 is pivotally supported by means of the pivot bolt 36 between the projecting ends of the laterally disposed strips 37 which are riveted to the free end 60 of the hammer shank, and preferably the hammer head has projecting from its inside face a sector 38 which is arcuately slotted as at 39, a bolt 40 passing through the strips 37 and through this arcuate slot. This bolt 40 65 is a clamping bolt and when set up will hold

the hammer head in any desired angular relation to the hammer shank within the limits of the slot 39.

The operation of my invention will be obvious.

Normally the spring 31 holds the hammer raised and the hammer shank in the position shown in dotted lines in Fig. 1 and the treadle 26 raised to the position shown in dotted lines in Fig. 1. Upon a depression of 70 the treadle 26 by the foot of the blacksmith the hammer will be drawn down and will strike the work supported upon the anvil. The strength of the blow thus struck may of course be regulated by the amount of 75 force applied to the treadle. I have found in practice that this force may be so applied that all of the ordinary work of the hammer may be performed. The leverage exerted by the lever 18 upon the hammer may be 80 changed by shifting the collar 32 along the hammer shank. In order to change the point of contact of the hammer with the anvil so as to cause the hammer to strike any particular part of the anvil it is only 85 necessary to release the clamping nut 13, whereupon the upper ends of the supporting members 11 may be shifted either toward or away from the anvil as the case may be, 90 sufficiently to cause the hammer to strike upon the inner margin of the anvil or the far margin thereof, or at the middle of the anvil. After the adjustment is made the nut 13 is turned up, clamping the members 11 in their adjusted position. In order to 95 cause the face of the hammer to strike at an angle to the face of the anvil I pivot the hammer upon the bolt 36 and provide the sector 38. By this means the angle of the hammer with relation to the shank is readily 100 changed and then the hammer locked in its position.

It will be noted that in my attachment the hammer is normally supported entirely away from over the face of the anvil thus 110 permitting the anvil to be used for other work and not in any way interfering with the ordinary use of the anvil. It is further to be noted that side strain is done away with by having the foot lever passed around 115 the anvil block and putting the foot pedal on a line with the hammer. Furthermore, it will be noted that the spring 31 is in its dormant position when the hammer is raised, or nearly perpendicular. This allows the 120 operator to start the hammer with very little strain upon the spring and thus start the hammer with relatively small amount of effort. It further permits the operator to start either slowly or quickly, and thus 125 either a light blow or a heavy blow can be secured.

By adjusting the hammer 35 with relation to the hammer shank or handle the hammer may be set to strike the work at any desired 130

angle, which is particularly useful in scarfing iron for welding, or in drawing out plantation plows and sweeps.

By the use of my device the blacksmith 5 can trim a plow and hammer it out, and weld wagon tires or do any other welding and accomplish a large amount of other like work, while at the same time his hands are free for properly manipulating the work on 10 the anvil. He can also hold the work upon the anvil with one hand, wield a hammer with the other hand, and operate the hammer 35 by means of his foot, and in fact in many cases do the work better than the work 15 can be done with a helper to do the hammering.

It is to be noted that in order to shift the hammer shank with relation to the anvil so as to change the point of contact between 20 the hammer face and the anvil, the hammer shank is raised by shifting the brace 8 upward upon the slotted supporting member 7, as illustrated in Fig. 2. This arrangement so alters the pivotal center for the shank 25 that the hammer may be used for striking downward and toward the front of the anvil, that is, downward and toward the member 5, instead of straight downward, and this may be done without altering the in- 30 clination of the hammer head itself. This is valuable in many classes of work, as for instance, in operating upon a piece of iron which is transversely curved or has an angular surface. Furthermore, the angle of the 35 face of the hammer head with relation to the anvil may be changed by rotating the hammer head upon the pivot 36 either independently of any upward and inward shifting of the hammer shank, or coördinately there- 40 with, so that if it is not required that the hammer shall strike downward and toward the member 5, or rather if it be not required that the face of the hammer, when it strikes the anvil, shall be relatively upward and to- 45 ward the front of the machine, the hammer may be so adjusted that it will strike flat upon the face of the anvil even though the hammer strikes upon the extreme rear face of the anvil.

50 My invention is simple, is very effective in practice, and may be easily removed or disassembled when it is not desired to be used, and may be very cheaply made.

Having described my invention, what I 55 claim is:

1. In a foot-operated hammer, upwardly extending supports, a hammer shank pivotally mounted between said supports, a hammer head adjustably mounted upon the hammer shank for rotation in a plane parallel thereto, the said supports being pivotally mounted at their lower ends whereby the hammer shank may be shifted longitudinally, and means for oscillating the hammer 60 shank.

2. In a foot-operated hammer, upwardly extending standards vertically slotted, supporting members disposed against the standards, a bolt passing through the supporting members and through the slots in the standards, a hammer shank pivoted between said standards, a hammer head mounted upon the shank for angular adjustment, and means for oscillating the hammer shank. 70

3. In a foot operated hammer, upwardly 75 extending standards, hammer shank supporting members pivoted to said standards, a hammer shank pivotally mounted between said supporting members, a brace pivotally supported at one end and having its free end 80 connected to said hammer shank supporting members, and an actuating treadle pivotally mounted upon said brace and operatively connected to the hammer shank.

4. The combination with an anvil, of vertically disposed standards arranged adjacent the anvil, a brace pivotally supported at one end and its free end disposed between said standards, upwardly extending hammer shank supporting members rigidly mounted 85 upon the free end of the brace and vertically adjustable therewith, a hammer shank pivotally supported between said members, a treadle pivotally supported upon the free end of the brace, and a link connecting said 90 treadle with the hammer shank.

5. In a foot-operated hammer, vertically disposed hammer shank supports, a hammer shank pivoted between said supports, a treadle pivotally supported adjacent the 100 lower ends of the hammer shank support and extending parallel to and beneath the hammer shank when it is lowered, and a link pivotally connected to the hammer shank adjacent its point of pivotal support and at its 105 other end pivotally connected to said treadle at a point approximately beneath the hammer head when the shank is in a horizontal position.

6. The combination with an anvil and a 110 supporting block therefor, of vertical standards spaced from the anvil, a pair of supporting members mounted upon said standards for vertical and angular adjustment, means for clamping these supporting members in adjusted positions, a hammer shank pivotally mounted between the upper ends of the standards, a hammer carried thereby, a brace pivotally mounted upon the anvil block and rigidly connected to said shank 115 supporting members for movement therewith, a treadle pivotally supported upon the brace, a spring connected at its lower end to said brace and at its upper end to the butt end of the hammer shank, and a link 120 pivotally connected to the hammer shank forward of its pivotal axis, the lower end of the brace being pivotally connected to the treadle adjacent the anvil supporting block. 125

7. The combination with an anvil, of ver- 130

5 tically disposed standards arranged adjacent the anvil, a brace disposed between the standards, vertically disposed hammer shank supporting members having their lower ends arranged on each side of said standards, a bolt passing through the standards and through the supporting members and through the end of the brace, said standards being slotted to permit the vertical movement of the brace, the bolt and the supporting members, clamping means on said bolt, braces rigidly connecting the upper ends of the supporting members to said brace, a hammer shank pivotally mounted between 10 the upper ends of the supporting members, a hammer carried thereby, a spring operatively connected to the rear end of the hammer shank and to said brace and acting to hold the hammer shank raised, a lever piv- 15 oted to the brace and having a treadle 20

mounted thereon, and a link operatively connecting said lever to the hammer shank between the pivotal point of the hammer shank and the hammer carried thereby.

8. In a foot operated hammer, a pair of 25 spaced vertically slotted members, a pair of standards disposed in engagement with the slotted members, means passing through said standards and through the slots of said members holding the standards in engagement with the members for vertical or angular adjustment, a hammer shank pivoted between the standards for oscillation, and means for oscillating the hammer shank. 30

35 In testimony whereof I hereunto affix my signature in the presence of two witnesses.

ASHTABULA GAINES.
